United States Patent [19]

Habicht

[11] Patent Number: Des. 304,834

[45] Date of Patent: ** Nov. 28, 1989

[54] ROTARY ACTUATOR

[76] Inventor: **Helmut Habicht**, 15 Royal Park Ter.,
Hillsdale, N.J. 07642

[**] Term: **14 Years**

[21] Appl. No.: **875,368**

[22] Filed: **Jun. 16, 1986**

[52] U.S. Cl. **D15/148**

[58] Field of Search **D13/1, 99; D15/5, 138,
D15/148, 149, 199; 92/52, 84, 88, 136, 138**

[57] CLAIM

The ornamental design for a rotary actuator, as shown and described.

DESCRIPTION

FIG. 1 is a front elevation view of a rotary actuator showing my new design.

FIG. 2 is a rear elevation view thereof.

FIG. 3 is a right end elevation view thereof.

FIG. 4 is a left end elevation view thereof.

FIG. 5 is a bottom plan view thereof.

FIG. 6 is a rear elevation view of a second embodiment

of my new design, with the front elevation view being

the same as shown in FIG. 1.

FIG. 7 is a left end elevation view relative to FIG. 6.

FIG. 8 is a right end elevation view relative to FIG. 6.

FIG. 9 is a bottom plan view relative to FIG. 6.
